UNITED STATES PATENT OFFICE.

GUSTAV FREIWALD, OF PORTLAND, OREGON.

HAT-FASTENER.

1,276,638.

Specification of Letters Patent. Patented Aug. 20, 1918.

Application filed February 26, 1918. Serial No. 219,291.

To all whom it may concern:

Be it known that I, GUSTAV FREIWALD, a citizen of the United States, residing at Portland, in the county of Multnomah and State of Oregon, have invented certain new and useful Improvements in Hat-Fasteners, of which the following is a specification.

This invention relates to that class of hat fasteners particularly adapted for securing women's hats to the hair in which two substantially parallel and preferably curved prongs are employed at each side of the hat.

The object of the invention is to provide a simply constructed and efficient fastener of this character which may be applied to the inner face of a hat between the side walls thereof and the lining so that when not in use it will be completely obscured and out of the way and may be readily projected when necessary.

With the foregoing and other objects in view, which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings:—

Figure 1 represents a transverse vertical section of a portion of a hat with this improved fastener shown applied with the prongs projected in dotted lines and retracted in full lines,

Fig. 2 is a front elevation with the prongs shown projected, the fastener being detached,

Fig. 3 is a detail perspective view of the prongs and their locking element detached, and

Fig. 4 is a detail sectional view taken on the line 4—4 of Fig. 2.

In the embodiment illustrated, a portion of a hat H is shown having the usual brim B and crown C with a lining L arranged therein. This invention comprises a plate 1, here shown rectangular, although obviously it may be of any other desired configuration, and which is composed preferably of metal, although it may be composed of other suitable stiff material. This plate has apertures 2 arranged around the edge thereof to provide for its attachment to the crown of the hat or the lining as may be

found desirable. The plate is also provided with a pair of transversely aligned laterally spaced slits 3 near one edge and at a point spaced inwardly therefrom and in longitudinal alignment therewith are a pair of keepers 4 formed by striking out the material of the plate as is shown clearly in Fig. 2. One wall of each of the slits 3 is offset relatively to the other so as to permit the free passage between them of the attaching or fastening prongs presently to be described.

These keepers and slits form guides for a pair of prongs 5 which are arranged in parallel relation and preferably provided at their free ends with rounded or ball-shaped terminals 6. These prongs 5 are curved longitudinally as shown in Figs. 1 and 3 to adapt them to conform to the shape of the head of the wearer and to enter the hair at the proper angle, and they may be composed of celluloid, bone, metal or any suitable material. These prongs 5 are connected at their inner ends by a locking plate 7 which has journals 8 at its opposite ends mounted in bearings formed in the inner ends of the prongs. This plate 7 is cam-shaped and is provided with a finger grip in the form of a lip 9 on its free edge, it being pivoted to the prongs eccentrically so that when shut down into the position shown in dotted lines in Fig. 1, the prongs will be locked in projected position. To release the prongs and retract them, the plate 7 is swung downwardly to the full line position shown in Fig. 1, which will operate to slide said prongs downwardly through the guides 3 and 4 between the hat lining L and its crown and thereby obscure and position them so as not to interfere with the placing of the hat on the head of the wearer.

From the above description, it will be obvious that this simply constructed device, while cheap to manufacture, and easily applied, will, when the prongs 5 are projected, securely retain the hat on the head of the wearer and prevent all possibility of its being blown off or accidentally dislodged.

From the foregoing description, taken in connection with the accompanying drawings, the advantages of the construction and of the method of operation will be readily apparent to those skilled in the art to which the invention appertains and while I have described the principle of operation of the invention together with the device which I

now consider to be the best embodiment thereof, I desire to have it understood that the device shown is merely illustrative and that such changes may be made as are within the scope of the claimed invention.

5 I claim:

A fastener of the class described comprising an attaching plate having means for connecting it to a hat and provided with a pair 10 of transversely alined laterally spaced slits, a pair of keepers arranged in said plate in

longitudinal alinement with said slits, a pair of prongs slidably mounted in said slits and keepers, a cam locking plate having a finger grip at its free end for actuating said plate 15 to retract and project said prongs.

In testimony whereof I affix my signature in presence of two witnesses.

GUSTAV FREIWALD.

Witnesses:

W. H. POWELL,
GEO. W. CALDWELL.
